UNITED STATES PATENT OFFICE

132,906

DESIGN FOR A COMMEMORATIVE SERVICE FLAG OR SIMILAR ARTICLE

Ernest D. Chase, Winchester, Mass.

Application March 24, 1942, Serial No. 106,308

Term of patent 7 years

To all whom it may concern:

Be it known that I, Ernest D. Chase, a citizen of the United States, residing at Winchester, in the county of Middlesex, State of Massachusetts, have invented a new, original, and ornamental Design for a Commemorative Service Flag or Similar Article, of which the following is a specification, reference being had to the accompanying drawing, forming part thereof, in which,

The figure is a face view of a commemorative service flag or similar article showing my new design which has no substantial thickness.

I claim:

The ornamental design for a commemorative service flag or similar article, as shown and described.

ERNEST D. CHASE.
